CLAIM

The ornamental design for an adapter for camera lens, as shown and described.

DESCRIPTION

FIG. 1 is a Front view of an adapter for camera lens showing our new design;

FIG. 2 is a Back view thereof;

FIG. 3 is a Top view thereof;

FIG. 4 is a Bottom view thereof;

FIG. 5 is a Left view thereof;

FIG. 6 is a Right view thereof; and,

FIG. 7 is a Front Perspective view thereof.

The broken lines show portions of the adapter for camera lens that form no part of the claimed design.
